UNITED STATES PATENT OFFICE.

CHARLES F. PEASE, OF CHICAGO, ILLINOIS, ASSIGNOR TO THE C. F. PEASE COMPANY, OF CHICAGO, ILLINOIS, A CORPORATION OF ILLINOIS.

WINDING MEANS.

1,102,353.

Specification of Letters Patent.

Patented July 7, 1914.

Original application filed July 19, 1912, Serial No. 710,472. Divided and this application filed December 16, 1912. Serial No. 737,089.

To all whom it may concern:

Be it known that I, CHARLES F. PEASE, a citizen of the United States, residing at Chicago, in the county of Cook and State of Illinois, have invented certain new and useful Improvements in Winding Means, of which the following is a specification.

The present invention is disclosed in my co-pending application for coating machine, filed July 19, 1912, bearing Serial No. 710,472, but is not claimed in such original application, the present application being a division of the same.

The present invention relates to novel means for winding paper or other flexible material into rolls or the like, in an expeditious manner.

An important object of this invention is to provide means to take or wind up the discharging or free end of a section or strip of coated paper or other flexible material, such means being adapted to wind up the paper faster than it is being fed longitudinally, so that if a considerable amount of slack occurs in the paper during the continuous longitudinal travel of the same, such slack will be taken up by the winding means without interfering with the operation of the machine which effects the longitudinal travel of the paper, such winding means, however, being so constructed that it does not exert undue pulls upon the paper, which might tear or otherwise injure the same, when there is no slack in such paper.

A further object of my invention is to provide means of the above mentioned character, which are simple in construction, reliable in operation, and not liable to derangements.

Other objects and advantages of this invention will be apparent during the course of the following description.

In the accompanying drawings forming a part of this application and in which like numerals are employed to designate like parts throughout the same, Figure 1 is a central vertical sectional view through the device, and, Fig. 2 is a horizontal section taken on line 2-2 of Fig. 1.

In the drawings, wherein for the sake of illustration, I have shown a preferred embodiment of my invention, the numeral 3 designates vertically spaced brackets (only one being shown), comprising upper hori-

zontal and depending substantially vertical arms 4 and 5. Suitably mounted between the free ends of the horizontal arms 4 is an idler roll 6. I provide driving means, preferably comprising an upper roll 7, pivotally connected with the arms 4 and engaged by a plurality of belts 8, extending downwardly to engage a positively driven roll 9, which in turn is mounted between the lower ends of the vertical arms 5, as shown. The means for positively rotating the driving rolls 7 and 9 is not shown, it being understood that any suitable means may be employed. In my co-pending application, above referred to, the driving means is shown as comprising sprocket wheels rigidly connected with the rolls 7 and 9, and driven by a sprocket chain.

I provide a novel form of winding means, comprising a vertically swinging structure, including depending arms 10, which are pivotally connected with the brackets 3 at their upper ends so that the lower ends of said arms are free to swing toward and away from the positively driven roll 9. The lower ends of the vertically swinging arms 10 are provided with enlarged heads 11, adapted to operate outwardly of the ends of the roll 9. These enlarged heads 11 are provided with pockets 12 for receiving a readily removable winding tube or element 13. As more clearly shown in Fig. 1, I provide a semi-cylindrical clamp 14, which is removable upon the winding tube 13 and serves to attach the free end of the paper to said tube. This clamp is shorter than the winding tube. The heads 11 carry bearing-rollers 15, which engage the winding tube 13. The outer sides of the pockets 12 are entirely open, as shown, whereby the winding tube 13 may be readily removed by an outward or upward movement. This winding tube 13 is rotated by driving connecting means, preferably in the form of belts 16, which engage the end portions thereof outwardly of the clamp 14 and the ends of a preferably larger feeding roll or element 17, which larger roll or element has engagement with the belts 8, the paper passing therebetween. It is seen that the winding tube 13 is rotated at a higher rate of speed than the larger feeding roll 17. The paper 18 is passed outwardly about the roll 6, between the belts 8 and the roll 17 and then

attached to the winding tube 13 by means of the clamp 14. The feeding movement or advancement of the paper is effected by the positively driven rolls 9, 7, 17, the associated tapes and the winding tube 13. The winding tube 13 is capable of being driven at a higher rate of speed than the feeding roll 17, as above stated, whereby it has a tendency to wind up paper faster than it is advanced or fed. During the ordinary feeding movement of the paper, the speed of rotation of the winding tube 13 is automatically reduced to correspond to that of the paper fed means, by virtue of the fact that the belts 16 are adapted to slip upon the tube 13, when sufficient pull is exerted upon the paper, which might tend to tear it. The slipping action of the belts 16 may be obtained by having the outer portions of the winding tube 13 lubricated or by having the belts 16 of the desired tension, or both. Stops or the like (not shown) are preferably provided to limit the downward movement of the swinging arms 10, whereby the winding tube 13 is retained spaced from the roll 9 and the roll of paper when first wound upon the winding tube is also held spaced from the roll 9. When, however, this roll of paper increases sufficiently in size, it engages the roll 9 and the belts 8, which aid in the rotation of the roll of paper. When the roll of paper which is being wound, is removed, the feeding movement of the paper continuing, the paper is cut and the tube 13 removed. This tube is now removed from the roll of paper and returned to its normal position in the winding means and the free end of the paper is attached thereto, as hereinabove stated. During the removal of the first roll of paper, the discharge of the paper continuing, there will be quite a lot of slack in the paper, which will be taken up during the continuous discharge of said paper, by virtue of the fact that the winding tube 13 is driven faster than the roll 17. It is obvious that at first this mechanical advantage is very slight, but as the side of the roll of paper being wound increases, said mechanical advantage also increases. It is thought that no further description of the operation of the device is necessary.

It is to be understood that the form of my invention herewith shown and described is to be taken as a preferred example of the same, and that certain changes in the shape, size and arrangement of parts may be resorted to without departing from the spirit of the invention or the scope of the subjoined claims.

Having thus described my invention, I claim:—

1. In apparatus of the character described, the combination with a plurality of spaced rolls, of a belt engaging the same

and driven thereby, a feeding roll for operating the belt, a swinging structure disposed near and upon one side of the belt, a winding roll carried by the swinging structure, and a belt engaging the feeding and winding 70 rolls.

2. In a machine of the character described, winding means including, an endless belt, means to drive the endless belt, a vertically swinging support disposed near the endless 75 belt and movable toward and away from the same, a feeding roll disposed near the upper end of the support to be driven by the endless belt by pressing the paper passing thereabout into engagement with the endless 80 belt, a winding roll carried by the lower end of the vertically swinging support to have the paper wound thereabout to form a paper roll increasing in diameter during the winding operation whereby the paper roll will 85 itself engage the endless belt and be directly driven thereby, and separate means operated by the feeding roll to rotate the winding roll.

3. In a machine of the character described, 90 means for winding paper or the like into a roll, comprising an endless conveyer structure, a feeding roll operating in engagement with the endless conveyer structure, a supporting structure movable toward and 95 away from said endless conveyer structure, a winding roll carried by the supporting structure, and belts engaging the feeding and winding rolls.

4. In apparatus of the character described, 100 paper feeding means, driving means therefor adapted to receive the paper between the same and the paper feeding means, a rotatable winding element arranged near the paper feeding means and bodily movable 105 toward and away from the same, and lost motion driving connecting means between the paper feeding means and the rotatable winding element.

5. In winding means of the character described, an endless belt, means to drive the endless belt, a pivoted support disposed near the endless belt to swing in a substantially vertical plane toward and away from the same, a feeding roll disposed at the pivot 110 point of the support, a winding roll carried by the lower end of the pivoted support to have the paper wound thereabout to form a paper roll increasing in diameter during the winding operation whereby the paper roll 115 will itself engage the endless belt and be directly driven thereby, and belts trained about the feeding roll and the winding roll.

6. In winding means of the character described, an endless belt, means to drive the 125 endless belt, a support movable toward and away from the endless belt, a winding roll carried by one end of the support to have the paper wound thereon for forming a paper roll increasing in diameter during 130

- the winding operation whereby the paper roll will itself engage the endless belt and be directly driven thereby, and means driven by the endless belt to drive the winding roll.
- 5 7. In winding means of the character described, relatively stationary driving mechanism, a pivoted support disposed near the driving mechanism and adapted to swing in a vertical plane toward and away from the
- 10 same, a large feeding roll disposed near the upper end of the pivoted support and engaging the driving mechanism to be operated thereby, a small winding roll carried by the lower end of the pivoted support to
- 15 have the paper wound about the same for forming a paper roll increasing in diameter during the winding operation whereby the paper roll will itself engage the driving mechanism and be directly rotated thereby,
- 20 and belts trained about the large and small rolls and of a proper tension so that the same will normally serve as positive driving connecting means and a lost-motion driving connecting means when the winding roll is
- 25 held against rotation.
8. In apparatus of the character described, paper feeding means, driving means therefor receiving the paper between the same and the paper feeding means, a rotatable winding element, a movable support for the 30 winding element whereby it may move toward and away from the driving means, and driving connecting means between the paper feeding means and the winding element.
9. In apparatus of the character described, 35 the combination with a paper feeding roll, driving means therefor receiving the paper between the same and the paper feeding roll, a rotatable winding element arranged in coöperative relation with the feeding roll, 40 means whereby the winding element may move laterally toward and away from the driving means, and means to rotate the winding element.

In testimony whereof I affix my signature 45
in presence of two witnesses.

CHARLES F. PEASE.
